COMBINED CATALYTIC HEATER AND PROTECTIVE COVER THEREFOR

Benjamin C. Baugh, Wichita, Kans., assignor to The
Coleman Company, Inc., Wichita, Kans.

Filed Feb. 17, 1971, Ser. No. 116,300

Term of patent 14 years

Int. Cl. D23—03

U.S. Cl. D23—123

FIG. 1

FIG. 2

FIG. 3

FIG. 1 is a front elevational view of a combined catalytic heater and protective cover therefor showing my new design, the rear having substantially the same appearance;

FIG. 2 is a side elevational view thereof on a reduced scale;

FIG. 3 is a top plan view thereof on a reduced scale.
I claim:

The ornamental design for a combined catalytic heater and protective cover therefor, as shown and described.
